UNITED STATES PATENT OFFICE.

JAMES E. WILLIAMSON, OF BERLIN, WISCONSIN.

MERCHANT'S STAND FOR PAPER BAGS.

SPECIFICATION forming part of Letters Patent No. 286,099, dated October 2, 1883.

Application filed August 1, 1883. (No model.)

To all whom it may concern:

Be it known that I, JAMES E. WILLIAMSON, of Berlin, in the county of Green Lake, and in the State of Wisconsin, have invented certain new and useful Improvements in Merchants' Stands for Paper Bags, &c.; and I do hereby declare that the following is a full, clear, and exact description thereof.

My invention relates to devices for suspending paper bags, &c., above a store-counter, or at other convenient points; and it consists in certain peculiarities of construction, as will be more fully set forth hereinafter.

In the drawings, Figure 1 is a perspective view of the preferred form of my device in operation. Fig. 2 is a detail view, showing a modified form of attachment of the holding-wires; and Fig. 3 shows yet another modification.

20 A represents the standard of my revolving holder, made of either wood or metal, and designed to be secured to a store-counter at its base *a*, as shown.

25 B is a collar adjustably secured to the standard A, at any elevation desired, by means of a set-screw, *b*, which collar is reduced to form a seat or shoulder for the reception of the base-ring or circular plate C of the wheel D, which has a similar upper ring or circular plate, C', 30 both of these rings encircling the standard A, as shown. From the upper ring-plate, C', rods *d* extend radially outward, being horizontal as far as the outer ring, D', of said wheel, beyond which they project downward, as shown at *d'*, 35 and from these horizontal rods *d* there extend other rods or braces, *e*, inward and downward to or through the lower ring-plate, C, being soldered or otherwise rigidly secured at their points of contact, and preferably terminating 40 in hook *e'* and *e''* at each end.

In the form of device illustrated in Fig. 1 I have shown the rim D' of the wheel D as being octagonal in form; but it might be made with any number of sides and angles required—such 45 as a heptagon, hexagon, or other polygon—or even circular; but I find the arrangement shown convenient for ordinary purposes, there being usually not more than eight sizes of paper bags in common use on merchants' counters; and in 50 order to readily turn the wheel and its contents I either extend one of the rods or braces *e* down-

ward, as shown at *e'*, or else secure an independent rod to the lower ring-plate, C, and at the bottom of this rod or extension *e'*, I secure it to a strap or plate, A', having a loop or grasp, 55 *a'*, wholly or partially encircling the standard A, as shown. This serves to steady the wheel D and enable it to be quickly and easily turned without binding upon the standard, and without the necessity of reaching up as high as the ring-plate C, which is usually at a considerable elevation above the counter.

The paper bags are suspended upon pointed wires E, which extend from one of the projecting rods *d* to the next one, and so on in succession, the ends of these wires E resting in or on hooks or catches formed on or secured to the said projecting rods *d*. I have shown various forms of such hooks or catches, and correspondingly varied forms of the wires E also. For instance, in Fig. 1 the catches F are each represented as a strip of angle metal secured to the rod-extensions *d*, the upper flange of the catch being perforated to allow the pointed end *e'* of the wire E to project through, while the butt or 75 rear end, *e*, of the next wire rests within the hook *f* of the said catch, and in said Fig. 1 this rear end, *e*, is only the plain blunt end of the wire, which is prevented from slipping too far by reason of the upturned or angle flange of 80 the catch F, already described.

In Fig. 2 the catch F is a plain strip of metal or other material with an upturned hook, *f*, and perforated just back of this hook to receive the hook at the rear end, *e*, of the pointed wire 85 E, while in Fig. 3 the catch F is formed of a wire bent to form the hook *f* at its end, and the rear end, *e*, of the pointed wire E is in this instance bent into a loop adapted to fit over said hook, while the point *e'* of the wire rests 90 within the hook of the next catch, as shown. These forms are merely matters of detail, and may be varied infinitely without departing from the spirit of my invention, which invention may further be embodied in a stationary 95 as well as a movable or revolving holder, as illustrated in Fig. 3.

In using my device one of the wires E is thrust through a bunch of paper bags of a given size, near the tops of said bags, and then the 100 said wire, thus loaded, is secured upon the catches of the holder in one of the ways illus-

trated; and I usually secure a plate, G, bearing a number indicative of the size of bag, upon the outer ring, D', of the wheel, or at other convenient point just above each wire that sustains the bags, so as to indicate, when any particular wire is empty, the size of bags that are to go upon it. The hooks c' and c² will be found very handy to hang extra-sized bags or other articles upon, when it is desired to further utilize my device in such manner, without disturbing the wires E, which hold the regularly-assorted sizes of paper bags.

Having thus described my invention, what I claim as new, and desire to secure by Letters 15 Patent, is—

1. In a device for holding paper bags, &c., the combination of an upright standard provided with an adjustable collar, with a revolving wheel supported on said collar, and bearing 20 hooks or catches and pointed wires for holding the bags, &c., adapted to extend between and be secured by each adjacent pair of the

hooks or catches on the said wheel, substantially as set forth.

2. In a device for holding paper bags, &c., 25 the combination of an upright standard provided with an adjustable collar, with a revolving wheel having a base-ring or circular plate supported on said collar, the revolving wheel having hooks or catches and pointed wires for 30 holding the bags, &c., and the base-ring having a downward-extending rod or brace, provided at its bottom with a strap or plate having a loop or grasp wholly or partially encircling the upright standard, substantially asset 35 forth, and for the purpose described.

In testimony that I claim the foregoing I have hereunto set my hand, on this 31st day of May, 1883, in the presence of two witnesses.

JAMES E. WILLIAMSON.
